UNITED STATES PATENT OFFICE.

JACOB FRIDRICH HUBER, OF PHILADELPHIA, PENNSYLVANIA.

DISPENSING APPARATUS.

1,164,350.

Specification of Letters Patent. Patented Dec. 14, 1915.

Application filed October 8, 1914. Serial No. 865,616.

To all whom it may concern:

Be it known that I, JACOB FRIDRICH HUBER, a citizen of the United States, residing in the city and county of Philadelphia, State of Pennsylvania, have invented 5 a new and useful Dispensing Apparatus, of which the following is a specification.

My invention consists of mechanism whereby a plurality of liquid materials may 10 be dispensed and directed simultaneously to one source of collection.

The invention is satisfactorily illustrated in the accompanying drawing, but the important instrumentalities thereof may be varied, and so it is to be understood that the invention is not limited to the specific details shown and described.

Figures 1 and 2 represent vertical sections at a right angle to each other of a dispensing 20 apparatus embodying my invention. Figs. 3 and 4 represent horizontal sections on line $x-x$, Fig. 1, certain parts thereof in one figure being in different positions from those in the other figure. Figs. 5 and 6 25 represent horizontal sections on line $y-y$, Fig. 1, certain parts thereof in one figure being in different positions from those in the other figure. Fig. 7 represents a horizontal section on line $z-z$, Fig. 1.

Similar numerals of reference indicate 30 corresponding parts in the figures.

Referring to the drawings, 1 designates a syrup can or other supplying vessel, the bottom of which is supported on a shoulder 35 on the exterior of the casing 2 of the rotary valve or plug 3. In the lower end of the said valve is the angular port 4, the upper limb of which is adapted to be placed in communication with the angular passage 40 5 which is formed in the offset 6 on the side of the casing 2, and extends vertically therein in it being in communication at the top with the can so as to direct the contents of the same to the upper limb of said port. The 45 lower limb of the latter is in communication with the nozzle 7 which is screwed into or otherwise connected with the lower end of the valve 3 and depends therefrom within the enlarged nozzle 8 which is secured to and 50 depends from the bottom of the casing 2, and consequently surrounds said nozzle 7.

On the side of the valve casing 2 is the chamber 9 which contains the horizontally arranged valve 10 whose seat 11 is on said casing. The outer end of the stem 10^x of 55 said valve is encircled by the spring 12

which bears against the cap 13 which closes said chamber 9 and against the said valve 10, so as to force the latter to said seat. The inner end of said stem freely enters the bore 60 14 of said seat, said chamber 9 having connected with it the soda conveying tube 15 which extends from a fountain so as to supply said chamber with such water.

In the valve or plug 3 is the channel 16 circumferentially thereon, the same being 65 in communication with the bore 14 leading from the valve seat 11 and being surrounded by the channel 17 circumferentially on the inner wall of the casing 2, the two channels 70 being in communication so that the inner end of the stem of the valve 10 may enter the same when said valve closes on its seat and cuts off the supply of soda from the chamber 9 to said channels, it being noticed 75 that in the side of the valve 3 are the ducts 18 which extend vertically therein from the channel 16 to the laterally extending ports 19 in the lower end of the casing 2, said ports opening into the nozzle 8 so as to discharge soda water into the latter when the valve 10 is open.

The nozzle 7 has on its side a shoulder 20 on which is seated the gasket 21, which bears 80 against the lower end of the casing 2 to 85 form a tight joint for the lower end of the valve 3 thereat.

In the valve 3 above the port 4 is the horizontally extending bore 22 in which is the pin 23, one end of which is adapted to engage 90 the inner end of the stem 10^x of the latter to open said valve and to leave the same to permit said valve to close, as will be hereinafter more fully explained. The pin 23 is movable in the bore 22 so as to adjust the 95 throw of the said valve 10, this being accomplished by means of the screw 24 which occupies the neck 25 on the side of the casing 2 and has its point adapted to contact 100 with one end of said pin so that the opposite end of the latter may engage with the stem 10^x and impart more or less throw thereto and consequently to the valve thereon. The head of said screw is covered by a suitable cap to cover and protect the same 105 and prevent tampering therewith. In the side of the lower portion of the casing 2 is fitted the screw 26 whose inner end 27 is beveled and adapted to enter the base of the syrup-conveying channel 5, and so adjust 110 the supply of the syrup to the port 4 and consequently to the discharge nozzle 7.

The outer end of the portion 28 of the casing which the screw 26 occupies is occupied by the cap 29 which closes the bore of said portion and covers the head of said screw 26 to cover and protect the same and prevent tampering therewith.

The lower end of the casing 2 has the circular groove or recess 30 therein, the same extending from one side port 19 to the other 10 in said end, so that they communicate whereby when the soda water discharges from the lower ends of the ports 18 it enters said groove 30 circulates therein and is distributed around the bottom of the casing whereby it reaches the several side ports 19 from whence it is injected in a comparatively large quantity or several streams into the nozzle 8, said grooves being closed from below by the gasket 21 which is held tightly 20 against said end of the casing by the shoulder 20 on the nozzle 7.

Projecting laterally from the upper end of the valve 3 is a pin 30*, which plays in a recess 31 in the upper end of the casing 2. 25 The ends of the said recess form stops 32 which indicate the open and closed positions of the valve. For the purpose of turning the valve the handle stem 33 is secured to it.

30 The operation is as follows:—The can is properly supplied with syrup and the tube 15 connected with the fountain or supply of soda water. When a drink is required the valve 3 is turned say one quarter whereby the port 4 is placed in communication with the passage 5 when the syrup flows from the can through said passage into said port and from thence into the nozzle 7 from the bottom of which it enters the drinking 35 glass vessel placed below it; simultaneously therewith, the pin 23 carried by the valve 3 engages the stem of the valve 10 and presses against the same moving the latter named valve from its seat when the soda water in the chamber 9 passes through the valve seat 11, the bore 14, the ducts 18, and the lateral ports 19 and so is injected into the nozzle 8 and from the latter into said drinking 40 glass or vessel, whereby the soda water and syrup are supplied to the latter at one operation and intermixed therein.

45 When the valve is turned one quarter in the opposite direction the port 4 is cut off from the passage 5, and thus the flow of syrup into the valve 3 ceases while the pin 13 carried by the valve is removed from the stem of the valve 10 and its end rotates in the grooves 16, and 17, whereby as said valve stem is no longer controlled by said pin, the 50 valve 10 under the action of the spring 12 closes on its seat, and thus the flow of soda water ceases, both flows being simultaneously cut off.

55 In the vessel 1 the handle rod is out of center, whereby a greater space exists at the

side of said rod toward the front of the vessel, so that the latter can be filled more conveniently at its top. When the vessel is placed perpendicular in position, as shown by the dotted lines Fig. 1, and all other parts are in harmony therewith, the discharge nozzle or outlet is thrown to the front so that the drinking vessel can be placed more conveniently under said outlet.

Having thus described my invention what 75 I claim as new and desire to secure by Letters Patent, is:—

1. In a dispensing apparatus for a plurality of materials, a supply vessel, a valve thereon, an auxiliary supply chamber, a valve in the latter, and a member loosely movable transversely through the first named valve adapted by the operation of the latter to engage with and open the second named valve.

2. In a dispensing apparatus for a plurality of materials, a supply vessel, a valve thereon, an auxiliary supply chamber, a valve therein, and a pin member in the first named valve adapted by the opening operation of the latter to engage with and open the second named valve.

3. In a dispensing apparatus, a supply vessel, a valve having its casing thereon, the latter having a passage therein leading from 95 said vessel, said valve having a port adapted to be placed in communication with said passage, a member on said casing at said passage to adjust the supply of material to said valve, a member loosely movable 100 transversely through said valve, and a second valve the opening of which is controlled by said member.

4. In a dispensing apparatus for a plurality of materials, a supply vessel, a valve 105 thereon, an auxiliary supply chamber, a valve therein, a pin member on the first named valve adapted by the opening operation of the latter to engage with and open the second named valve, and a device on said 110 casing adapted to engage said pin member to set the same relatively to the adjustment of the valve of the auxiliary chamber.

5. In a dispensing apparatus for a plurality of materials, a supply vessel, a valve connected with the latter and adapted to be placed in and out of communication therewith, an auxiliary supply chamber, a valve in the latter, a conveyer leading to said chamber, a member slidably mounted in said 115 first named valve adapted to engage the last named valve to open the same, and a plurality of discharging members respectively for said valves.

6. In a dispensing apparatus for a plurality of materials, a supply vessel, a valve having a port adapted to be placed in and out of communication with said vessel, an auxiliary supply chamber adapted to be connected with said valve and the casing 120

thereof, a valve in said auxiliary chamber, means on the first named valve for operating the last named valve to open the latter, a discharge nozzle connected with the casing of the first named valve, and a discharge nozzle connected with said first named valve, one nozzle being inclosed by the other nozzle.

7. In a dispensing apparatus for a plurality of materials, a supply vessel, a valve, 10 a casing for the latter on said vessel, said valve having a port adapted to be placed in communication with said vessel and having an outlet, an auxiliary chamber on said casing adapted to be placed in communication 15 with the latter and the first named valve, the latter having a port leading from said auxiliary chamber to an outlet, the first named valve having a laterally movable member thereon adapted by its opening operation to engage with and open the second named valve.

8. In a dispensing apparatus for a plurality of materials, a supply vessel, a valve, a casing for the latter connected with said 25 vessel and in communication therewith, an auxiliary supply chamber attached to said casing and in communication therewith, a valve in said chamber a slidable member in the first-named valve whereby the second- 30 named valve is adapted to be opened by the operation of the first named valve, a conveying tube leading to said chamber, and a plurality of discharging members connected respectively with said casing and the first 35 named valve.

9. In a dispensing apparatus for a plurality of materials, a supply vessel, a valve connected with said vessel adapted to be placed in and out of communication there- 40 with, an auxiliary receiving chamber on said casing, a valve in said chamber, discharge outlets respectively for said valves and means in the first valve in alinement with and designed for contact with the stem 45 of the last-named valve.

10. In a dispensing apparatus for a plurality of materials, a supply vessel, a valve, a casing for the latter connected with said vessel, an auxiliary supply chamber connect- 50 ed with said casing, a valve in said chamber, a movable member in the first-named valve for contact with the last-named valve, a port in said first named valve in commu-

nication with said vessel and having an outlet leading from said valve, a nozzle on said 55 casing with which said outlet is in communication, a port in said valve leading from the valve of the auxiliary supply chamber and having an outlet at the base of said casing, and a discharge nozzle for said casing at 60 the last named outlet.

11. In a dispensing apparatus, a supply vessel, a valve having a port adapted to be placed in and out of communication with said vessel, a casing containing said valve, 65 the port of the latter having an outlet at its lower end, an auxiliary supply chamber connected with said casing in communication therewith, a valve in said chamber, a plurality of ports in said valve leading from 70 said chamber, the outlets of said ports being at the lower end, the latter having a groove therein forming communications for said outlets one from the other, means for closing the underside of said groove, said 75 end having therein discharge ports which are in communication with said groove.

12. In a dispensing apparatus, a supply vessel, a valve therefor, the same having a port therein, one end of which is in communication with said vessel, a discharge nozzle connected with the outlet end thereof, a casing for said valve, an auxiliary supply chamber connected with said casing, a valve in said chamber, a port in said first named 80 valve leading to the bottom of said casing, a distributing discharge recess in said bottom, a shoulder on said nozzle, and a gasket adapted to be seated on said shoulder and being interposed between the same and the 85 lower end of said casing, and serving to close the under side of said recess.

13. In a dispensing apparatus, a supply vessel, a valve casing having an outlet passage in the body of said casing in communication with said vessel, a shoulder on said casing on which said vessel is supported in an inclined position, a rotatable valve in said casing, and an operating rod which is connected with said valve and rises there- 90 from in normally perpendicular direction in said inclined-supported vessel.

JACOB FRIDRICH HUBER.
